UNITED STATES PATENT OFFICE

FREDERICK T. RUSSELL, OF UTICA, NEW YORK, ASSIGNOR, BY MESNE ASSIGNMENTS, TO FOX COMPANY, OF PHILADELPHIA, PENNSYLVANIA, A CORPORATION OF PENNSYLVANIA

TOY GUN

Application filed April 11, 1930. Serial No. 443,279.

This invention relates to toy guns and more particularly to those guns in which a relatively light ball is projected out of the barrel of the gun and toward a mark by the impact of a spring-impelled plunger.

The object of the present invention is to provide a toy gun which is outward appearance closely resembles a real rifle, that is to say, a firearm, although the frame, barrel and trigger guard of the present invention are stamped and formed from a single integral piece of sheet metal.

A further object of my invention is to provide a toy rifle in which a ball may be inserted through an opening in the wall of the barrel into a chamber provided in the barrel where the said ball is retained until the gun is cocked, and to provide a structure wherein when the gun is cocked, the ball drops gravitationally into a position in which it is in alinement with and in advance of a strikepin whereby the impact of the said strikepin on said ball upon the release of a spring-impelled plunger projects the ball out of the chamber and through the barrel in the direction of the mark or target aimed at.

Further objects of my invention are to provide simple means for rigidly securing an impact block and a ball receiving block in the barrel against displacement; for maintaining the major portion of the plunger rod in substantial alinement with the axis of the barrel; and to provide the rear end of the rod with integral bent portions to cooperate with a stationary spring abutment and a slot through the frame to prevent a rotation of the plunger within the barrel and to prevent undue motion of the grip toward and away from the frame or about the axis of the plunger rod.

A further object of my invention is to make a faithful miniature model of a real rifle, of few parts, which are easily assembled at a low cost, durable and not subjected to any particular wear.

Other objects of this invention will appear in the specification and claims below.

Referring to the drawings forming a part of this specification and in which the same reference characters are employed through-

out the various views to designate the same parts,

Fig. 1 is a side elevational view, partly in section, of a toy rifle embodying my invention, with the operative parts of the gun shown in the cocked position.

Fig. 2 is a similar view showing the relative position of the parts after the gun has been fired.

Fig. 3 is a transverse vertical section on the line 3—3 of Fig. 1.

Figs. 4, 5, 6, 7 and 8 are vertical transverse sections of Fig. 1, taken on the lines 4—4, 5—5, 6—6, 7—7 and 8—8 respectively, on a scale larger than that of Figs. 1, 2 and 3.

Briefly, the barrel 1, the frame 2 and the trigger-guard 3 are made out of one sheet of metal stamping from which flanges 2^a, 2^b of the frame are struck or turned up around the side walls 2^b, 2^b of the frame 2, and the flanges 3^a, 3^a are struck up from the sides of the trigger-guard 3, all of said flanges being of such a height that when the part of the blank which forms the top 2^c of the finished frame 2 is bent into substantially semi-cylindrical form and the portions of the blank which form the barrel 1 are also bent into cylindrical form, with the side walls 2^b of the frame parallel, the flanges 2^a, 2^a project toward each other from opposite sides of the frame and abut against each other and the flanges 3^a, 3^a will also respectively abut against each other to close the bottom of the frame 2 and to provide a sturdy trigger-guard 3 of substantially rectangular shape in transverse cross-section. After having been bent into the shape shown in Fig. 3, it is then only necessary to spot-weld the flanges 2^a together as at the spot-weld 4 and to solder or spot-weld the abutting edges on the under-

side of the barrel at a single point, preferably by a spot-weld 5 at the point where the barrel is provided with a circumferential groove 6 which forms a rigid integral shoulder 7 on the inside of the barrel against which the forward end of the impact block 8 firmly abuts.

The portion of the barrel to the rear of the impact block 8 and between it and the forward end of the stationary rear abutment

9, provides a chamber 10 in which is mounted a piston or plunger 11 having a plunger rod 12 rigidly attached thereto, the major portion 12^a of which is straight and extends into the rear abutment 9 when the piston or plunger 11 is in engagement with the impact block 8. Surrounding the straight portion 12^a on the plunger rod is a coiled compression spring 13, the rear end of which is seated against the forward end of the said abutment 9 and the forward end of which surrounds and fits a projection 11^a forming the rear end of the piston or plunger 11.

The rear abutment 9 preferably comprises a cylindrical wooden rod provided with a relatively deep channel extending the full length of the rod, radially disposed and extending from the surface of the rod to a point beyond the axis of the rod. The plunger rod 12 slidingly fits between the vertical sides of the slot or channel 9^a. The forward end of said abutment 9 preferably fits into and is supported by the rear end of the cylindrical barrel 1 and the rear end of the abutment 9 is seated squarely against the forward end of the stock 14 which preferably telescopically fits into the open rear end of the frame 1 and is rigidly secured therein by bolts or rivets 15, 15.

The forward end of the stock 14 is preferably provided with a staple 16 or any other suitable flat projection which will fit into the slot 9^a and will hold the rear end of the abutment 9 firmly against the inside of the top 2^c of the frame and will also maintain the slot 9^a vertical and opening downwardly.

The rear end of the straight portion 12^a of the plunger rod terminates in a substantially vertical portion 12^b which extends out of the slot to a point below the abutment and the section or portion 12^b terminates in another section 12^c which is preferably straight and extends horizontally normal to the plane of the side 2^b of the frame 2 and out through a slot 17 in the side 2^b of the frame. Said slot 17 extends longitudinally parallel to the axis of the barrel 2, but its lower end forms a support or rest on which said horizontal portion or extension 12^c may freely slide. The outer end of the section 12^c terminates in a handle section 12^d provided with a knob or grip 18 by means of which one drawing backwardly or rearwardly on the grip 18, retracts the plunger 11 against the tension of the coiled propulsion spring 13.

Within the frame 2 is a trigger 19 mounted to turn on a pivot pin 20, said trigger being provided with a detent 21 which, under the expansive tension of the trigger spring 22, normally lies against the cylindrical surface of the abutment in the path of the movement of the portion 12^c on the plunger rod when the latter nears the rearward limit of its motion. When the grip 18 is drawn rearwardly the transverse horizontal section or

portion 12^c of the plunger rod engages the forward beveled edge of the detent 21 of the trigger 19, depresses it until the section 12^c passes to the rear of the detent 21, whereupon the spring 22 forces the detent upwardly to retain the plunger rod and plunger attached thereto in their rearmost position against the force of the compressed propulsion spring 13.

To fire the gun, it is only necessary to pull the trigger 19, thus releasing the plunger rod from its engagement with the detent, whereupon the spring 13 impels the piston or plunger 11 and the plunger rod 12 attached thereto, forwardly at a high speed until the plunger engages the rear face of the impact block 8.

The flanges 2^a 2^a of the frame 2 are recessed or cut away between the points where the trigger-guard joins the frame to provide a slot 23 to guide the projecting end of the trigger 19 in a straight path and to position the trigger on its pivot pin 20.

The forward end of the stock 14 is preferably provided with a recess 24 in which is seated the trigger ring 22, the forward end of which surrounds a suitable projection 19^a on the trigger. Any forward movement of the trigger substantially beyond the position shown in Fig. 2 is prevented by the engagement of the detent 21 with the cylindrical surface of the wooden abutment 9 at one side of the slot or channel 9^a.

Referring to Fig. 3 it will be observed that substantially all of the trigger within the frame is offset to a point substantially midway between the ends of the horizontal section 12^c of the plunger rod and after only the lower end of the trigger is vertically below the axis of the barrel or midway the sides of the trigger-guard to extend through the slot 23.

The impact block 8 is preferably made of hard wood, firmly seated against the shoulder 7 and is preferably retained in position by the extensions 25 in the metal of the barrel 1 extending into the wooden impact block 8, as is clearly shown in Fig. 6. Within the impact block 8 is also slidably mounted the strike-pin 26 in a hole 27 in the impact block 8 and a hole 28 in a head or washer 29 secured to the rear end of the impact block in any suitable manner, as by the integral tangs 30. Between the hole 27 and the head 29 is provided a chamber 31 in the impact block and within the chamber the strike-pin is provided with a flange or shoulder 32 between which and the hole 27 is a light spring 33 under compressive tension and surrounding the strike-pin 26 in its rearmost position with its forward end projecting rearwardly of the head or washer 29 and into the path of the reciprocation of the plunger 12.

In advance of the extension 6 and tightly fitting within the barrel 1, is the ball receiver 34 preferably comprising a cylindrical wooden plug or body provided with a ra-

dially disposed circular passage 35 of a diameter slightly larger than that of the projectile or ball 36. The upper end of this passage 35 preferably registers with a similar circular opening 37 through the top of the barrel. It is through this opening that the projectiles or balls 36 are inserted into the gun.

The ball receiver 34 is also preferably provided with a short axial bore coaxial with the barrel and formed through a head or projection 39 on the forward end of the body. To the rear of this head or shoulder 39, is a shallow annular groove 40 surrounding the body immediately in the rear of said head and in which is tightly wrapped and secured a light spring wire 41 having a free end 41^a brought forwardly over the edge of the head 39 and bent downwardly against the outer surface of said head and across an edge of the opening 38, said resilient end 41^a being operative to prevent a ball inserted into said radial hole or passage 35 and seated in said bore 38 from rolling forwardly gravitationally.

The ball receiver 34 is preferably securely held within the barrel against rotative movement about its axis by indentations 42 through the metal of the barrel and into the outer cylindrical surface of the wooden body or block forming the ball receiver 34.

The forward end of the strike-pin 26 is free to reciprocate through an opening 43 in the rear wall 34^a of the ball receiver in alignment therewith, so that no particular care has to be exercised in fitting and securing the impact block and the ball receiver in place within the barrel except to see to it that the radial passage 35 in the ball receiver is in axial alignment with the hole 37 in the barrel.

When the plunger 12 is retracted, as shown in Fig. 1 and the strike-pin 26 is in its rearmost position, having been moved over by the tension of the light spring 35, the forward end of the strike-pin is substantially flush with the forward surface of the rear wall 34^a of the ball receiver 34. But when the gun is fired and the plunger 12 comes to rest on the rear end of the impact block 8, the forward end of the strike-pin extends clear across the radial passage 35 and a ball inserted thereinto through the opening 37 will seat on the upper side of the strike-pin 26. When, however, the plunger is being retracted, the strike-pin 26 will follow the plunger until the flange or shoulder 32 strikes upon the forward surface of the metal head or washer 29 where it will come to rest, and in so moving rearwardly the forward end of the strike-pin will move out from under any ball resting thereon and will permit, when the strike-pin has reached its rearmost position, the ball or projectile 36 to be seated in the bore 38 on the ball receiver.

When, therefore, the plunger is released

and drives the strike-pin forwardly, the forward end of the strike-pin impinging against the ball or projectile 36, will force the ball over the light resilient end 41^a of the wire spring 41 and out through the barrel toward the mark aimed at.

For the purpose of enabling one to sight the gun at a given object, the forward end of the gun may be provided with an outwardly expressed projection to form a forward sight 44 and the rear end of the frame may be provided with a struck-up alined rear sight 45 provided with a circular opening 45^a through which the forward sight may be readily seen and the gun aimed in the desired direction.

The invention above described, greatly simplifies the construction of the impact block and ball receiver, since the strike-pin is mounted in the impact block coaxial with the axis of the barrel with the axis of the impact block and with the axis of the ball receiver.

The impact block with the strike-pin mounted therein, is a unit construction which may be bodily placed in the barrel and there retained stationarily with respect to the barrel, there being no force operative to move the impact block 8 forwardly from its seat and any rotative movement which may be imparted to the impact block due to the repeated blows impressed upon it by the plunger, do not interfere in the slightest with the operation of the device, because of the coaxial arrangement of the parts with respect to each other.

The ball receiver may also be made of simple construction of short length and of simple construction, comprising as it does but a short cylindrical plug having an axial bore and a radial passage communicating therewith, both of a diameter but slightly larger than that of the projectile to be placed in the receiver.

Having thus described my invention, what I claim and desire to protect by Letters Patent of the United States is:

1. In a toy gun, the combination of a frame and a barrel integral with each other and of sheet metal, said barrel being provided with a circumferential annular inwardly indented groove intermediate the ends of said barrel to form a rigid shoulder within the bore of said barrel, a spring-impelled, trigger-controlled impact plunger reciprocable within said barrel to the rear of said shoulder, an impact block fitting said bore in the rear of and seated against said shoulder, a longitudinally reciprocable strike-pin mounted in said impact member, and a light spring also mounted in said impact member and normally yieldingly holding said strike-pin in its rearmost position with the rear end of said strike-pin projecting into the path on the forward movement of said plunger, and a ball retainer fitting said bore of said barrel and fixedly po-

sitioned substantially against the forward shoulder provided by said circumferential groove, said ball retainer being provided with means for holding a ball in alinement with the forward end of said strike-pin when strike-pin is in its rearmost position.

2. In a toy gun, the combination of a frame and a barrel integral with each other and of sheet metal, said barrel being provided with 10 a circumferential annular inwardly indented groove, intermediate the ends of said barrel to form a rigid shoulder within the bore of said barrel, an impact block fitting said bore and in the rear of and seated against said shoulder, said impact block housing a longitudinally reciprocable strike-pin and means for normally yieldingly holding said strike-pin in its rearmost position with an end projecting rearwardly from said impact block, 15 20 a spring-impelled, trigger-controlled impact plunger within said barrel and in the rear of said impact block, the forward movement of which plunger is limited by said impact block, a strong propulsion spring in the rear 25 of said plunger, the tension of which normally holds said plunger squarely against said impact block, a ball retainer fitting said barrel and rigidly secured therein against longitudinal movement and having a passage 30 therein in alinement with said strike-pin and a lateral passage communicating therewith through the wall of said barrel for the insertion of projectiles into said ball retainer, means to yieldingly hold a ball in 35 said passage, the forward end of said strike-pin being in the rear of a projectile in said passage when the strike-pin is in its rearmost position and operative to drive said ball from said passage upon the movement of 40 said strike-pin to its forward position under the impact of said plunger.

3. In a toy gun, the combination of a frame and a barrel integral with each other and composed of sheet material, said barrel being 45 provided with a circumferential annular indented groove intermediate the ends of said barrel to form a rigid shoulder within the bore of said barrel, an impact block fitting said bore and seated against the rear side 50 of said shoulder, a spring-impelled, trigger-controlled plunger reciprocable within said barrel in the rear of said impact block, a propulsion spring operative to drive said plunger against said impact block, a longitudinally reciprocable strike-pin mounted in 55 said impact block substantially coaxial with said barrel, means mounted in said impact block and normally yieldingly holding said strike-pin in its rearmost position with its 60 rear end projecting into the path of the movements of said plunger, a ball retainer mounted in said barrel and provided with a short bore coaxial with said barrel and said strike-pin, with a transverse bore and a trans- 65 verse passage at the rear end thereof through

the wall of said barrel for the insertion of balls into said bore, yielding means secured to the forward end of said ball retainer and lying across the outer end of said bore to prevent a ball in said bore from rolling gravitationally out of the end of said barrel, the forward end of said strike-pin being substantially flush with the rear wall of said bore in its rearmost position and projecting into said bore in its forward position, whereby an impact of said plunger on the rear end of said strike-pin causes the forward end of said strike-pin to impinge upon said ball and impel it against the resistance of said yielding means out of the bore of said ball receiver and of said barrel.

4. In a toy gun, the combination of a frame, a barrel rigidly secured thereto and an impact block rigidly mounted in said barrel, a spring-impelled trigger-controlled impact plunger reciprocable within said barrel to the rear of said impact block, said impact block housing a longitudinally reciprocable strike-pin, a light spring also mounted in said impact block and normally yieldingly holding said strike-pin projecting into the path of the forward movement of said plunger and a ball retainer fixedly mounted in the bore of said barrel and forward of said impact block and adjacent thereto, said ball retainer being provided with means for holding a ball in alinement with the forward end of said strike-pin when said strike-pin is in its rearmost position, said strike-pin being operative to impinge against said ball and impel it out of said barrel upon the movement of the strike-pin to its forward position under the impact of said plunger.

In witness whereof, I have hereunto set my hand this 18th day of March, 1930.

FREDERICK T. RUSSELL.
